United States Patent Office

Des. 186,289
Patented Oct. 6, 1959

186,289

EXPANDED METAL SHEET OR THE LIKE

Donald E. Cooper, Bristolville, Ohio

Application October 24, 1958, Serial No. 53,138

Term of patent 14 years

(Cl. D54—2)

I claim:

The ornamental design for an expanded metal sheet or the like, substantially as shown.
